BOILER SKIMMER

Arthur A. Giesen, Chicago, Ill.

Application March 16, 1951, Serial No. 215,975

4 Claims. (Cl. 122—389)

1

This invention relates to a new and improved skimmer for boilers or the like and more particularly to a floating skimmer adapted to remove suspended and dissolved solids which are more concentrated at or adjacent the water surface when a boiler is in operation.

It is customary to reduce the concentrations of these solids through a continuous blow-off, having a stationary pipe located about six inches below the nominal water level, and a needle or orifice valve located outside of the boiler drum to control the rate of discharge. Such stationary outlets draw from an area generally adjacent to them and consequently are not fully effective. In operation the steam releasing surface becomes a fluctuating, turbulent zone and the stationary blow-off pipe may be above the water surface where it is entirely ineffective in removing impurities and results in waste of valuable steam. On the other hand the intake of the stationary blow-off pipe may be from points well below the surface and the result is loss of heated water with removal of comparatively small amounts of solids which are more concentrated at or adjacent the surface in an operating boiler.

The present invention is in the nature of a modification and improvement of the construction shown in my prior application, Serial No. 131,977, filed December 9, 1949, issued September 25, 1951, as Patent No. 2,569,160. Floating skimmers to be effective must be maintained at the proper depth relative to the water surface. It is important that they be maintained at specific locations in the boiler and not be allowed to float around freely in the boiler. The violent surface ebullition tosses a floating skimmer, and in moving boilers, such as on locomotives or steamships, there are violent surges and wave forming movements of the water.

It is an object of the present invention to provide a new and improved floating skimmer especially adapted for use in steam boilers, tanks and other containers wherever it is necessary to skim impurities at or adjacent the liquid surface.

It is another object to provide a shallow draft skimmer for use in boilers and the like which have only a few inches of liquid above boiler tubes or other internal structures or the bottom of the boiler or tank.

It is a further object to provide a skimmer having floats designed to minimize vertical movement of the skimmer due to local disturbances of the water surface.

It is an additional object to provide such a skimmer having fixed guides to maintain it in proper location in the boiler without constraining it against necessary vertical or tilting movement.

It is also an object to provide a skimmer of this type which is simple in design and construction and adapted for commercial production and use.

2

Other and further objects will appear as the description proceeds.

I have shown certain preferred embodiments of my invention in the accompanying drawings in which—

Figure 1 is a fragmentary elevation of a boiler showing the improved skimmer installed therein;

Figure 2 is a plan view of the skimmer of Figure 1, partly broken away; and

Figure 3 is a side elevation of the skimmer trough and associated parts of the skimmer shown in Figure 1.

In the form of construction shown in the drawings, the skimmer comprises the trough 11 having a flexible conduit 13 leading from a rotatable elbow 14 in the lower portion of the trough. Spaced connecting members 15 are secured to the ends of the trough by bolts 16 and extend outwardly from the ends. The cross frame members 17 are connected to the ends of the spaced connecting members 15. It is to be noted that the cross frame members are substantially longer than the width of the trough 11.

A pair of spaced guide members 19 are suspended from the hanger bracket 21 shown in Figure 1. The hanger bracket 21 is located in the upper portion of the boiler shell or drum 23 in which the nominal water level is indicated at 24. It will be understood that the guide members 19 may be secured to any suitable portion of a boiler structure with various types of mounting or hanging arrangements. These guide members 19 extend downwardly between the spaced connecting members 15. The lower ends of the guide members 19 are connected by a horizontal brace member 27 into which they are threaded, the central portion 28 of the brace member 27 being bowed to one side, as best shown in Figure 2, to provide a clearance for the rotatable elbow 14 and flexible conduit 13.

A pair of elongated floats 30 have their opposite ends secured to the cross frame members 17 at points 31. These floats 30 extend parallel to and spaced from the trough 11. Stop members 33 extend between the spaced connecting members 15 at points between the location of the spaced guide members 19 and the ends of the trough 11. It is to be noted that the relative spacing of the stop members with regard to the location of the guide members is such that the skimmer assembly cannot move a distance as to bring the ends of the trough in engagement with the guide members. As shown in Figure 1, the cross frame members 17 are provided with a plurality of the vertically aligned openings 35 so that the floats 30 may be secured to these members 17 at different levels, as desired. This makes it possible to adjust the floating level of the trough relative to the surface of the liquid.

The screen 37 is preferably formed of sheet metal and is generally V-shaped in cross-section, as best shown in Figure 1, with its lower cen-

tral portion located immediately adjacent the upper surface of the trough 11. The side portions of the screen 37 are inclined upwardly and outwardly so that they are spaced above the trough edges and the outer edge portions 38 of the screen 37, in the construction shown, are located closely adjacent the upper portion of the inner faces of the floats 30. In the construction shown, the central portion of the screen 37 is secured to the inturned upper end flanges 40 of the trough 11. These flanges 40 are reinforced by strips 42 which may be welded to their under faces and screws 43 are passed through washers 45 and through openings in the screen 37 and are threaded into the reinforced flanges 40. The central portion of the screen 37 is preferably unperforated as shown in Figure 2 while the lateral portions are perforated.

The operation of the skimmer construction shown will be apparent from the above description, the skimmer being installed in the boiler and adjusted to float at the surface or submerged to a predetermined depth below the surface and being located by means of the guide members 19. The spaced and elongated floats 30 are of such a character as to reduce tilting of the skimmer assembly due to fluctuation of surface levels in the turbulent steam release zone as the water boils. The construction is such that the skimmer will not bind against the vertical guide members 19 and will be free to tilt within necessary limits. The stop members 33 are cylindrical in cross-section and present rounded surfaces for contact with the guide members 19. The spacing of the parts is such that the ends of the trough cannot engage the guide members 19 to cause wear or to bind against them.

While I have shown certain preferred embodiments of my invention in the accompanying drawings, these are to be understood to be illustrative only as the construction may be varied to meet different conditions and requirements and I contemplate such modifications as come within the spirit and scope of the appended claims.

In the claims:

1. In a skimmer for removing suspended and dissolved solids from fluids in boilers and the like, an elongated trough, a conduit leading from the lower portion of the trough, spaced connecting members extending from each end of the trough, cross frame members connected to the ends of the connecting members, said cross frame members being longer than the width of the trough, elongated float members extending parallel with and spaced from the edges of the trough and connected at each end to the cross frame members, and a screen located above the trough, said screen being generally V-shaped in cross section with the center of the V extending along adjacent the center line of the top of the trough and its side portions located above and spaced from the trough.

2. In a skimmer for removing suspended and dissolved solids from fluids in boilers and the like, an elongated trough, a conduit leading from the lower portion of the trough, spaced connecting members extending from each end of the trough, cross frame members connected to the ends of the connecting members, said cross frame members being longer than the width of the trough, elongated float members extending parallel with and spaced from the edges of the trough and connected at each end to the cross

frame members, and a screen located above the trough, said screen being generally V-shaped in cross section with the center of the V extending along adjacent the center line of the top of the trough and its side portions located above and spaced from the trough, the screen being wider than the trough and extending adjacent the floats.

3. In a skimmer for removing suspended and dissolved solids from liquids in boilers and the like, an elongated trough, a flexible conduit leading from the lower portion of the trough, spaced connecting members extending from each end of the trough, cross frame members connected to the ends of the spaced connecting members, floats connected to the cross frame members, a pair of spaced guide members adapted to be secured to a boiler structure, one of such guide members extending vertically in the space at each end of the trough between the trough, the spaced connecting members and the cross frame members, the guide members being spaced apart a distance greater than the length of the trough, and stop members extending between the connecting members and located between the guide members and cross frame members, the relative spacing being such that the stop members prevent the guide members from contacting the ends of the trough.

4. In a floating skimmer for removing suspended and dissolved solids from liquids in boilers and the like, an elongated trough, a flexible conduit leading from the lower portion of the trough, spaced connecting members extending from each end of the trough, cross frame members connected to the ends of the spaced connecting members, said cross frame members being longer than the width of the trough, elongated floats on each side of the trough and spaced therefrom, the ends of the floats being adjustably connected to the cross frame members, a screen secured adjacent the upper face of the trough with its lateral portions inclined upwardly and extending above and spaced from the trough and adjacent the floats, a pair of spaced guide members adapted to be secured to a boiler structure, one of such guide members extending vertically in the space at each end of the trough between the trough, the spaced connecting members and the cross frame members, the guide members being spaced apart a distance greater than the length of the trough, and stop members extending between the connecting members and located between the guide members and cross frame members, the relative spacing being such that the stop members prevent the guide members from contacting the ends of the trough.
